SHEDDING MECHANISM FOR LOOMS

William R. Hewton, Philadelphia, Pa., assignor to
 Collins & Aikman Corporation, Philadelphia,
 Pa., a corporation of Delaware

Application January 24, 1951, Serial No. 207,599

17 Claims. (Cl. 139—56)

1

This invention relates to shedding mechanisms for looms and particularly to means for providing automatic reverse motion for such mechanisms. More specifically, it is concerned with shedding mechanism of the head motion or dobby type, wherein the warp harnesses are raised and lowered to change the sheds, as required during the weaving, by means of jacks which are selected for operation in a prescribed order through interposed actuating instrumentalities, under control of an intermittently-progressed pattern chain. In the event of a mispick or weft failure, due either to rupture or bobbin exhaustion, the loom must be reversed and the pattern chain of the head motion must be re-set to operate the warp harnesses in proper timed relation when weaving is resumed after recovery and tying of the broken weft ends, or after weft replenishment, as the case may be. With shedding mechanisms as ordinarily constructed, numerous time-consuming adjustments have to be made before the head motion can be re-set, requiring the exercise of considerable skill on the part of the loom attendant or weaver. Moreover, the head motion, and in fact the entire loom, must be reverse operated manually at the expenditure of great physical effort.

My invention is directed in the main toward overcoming the above pointed out disadvantages which are inherent in the looms of the prior art. This objective is realized in practice, as herein-after more fully disclosed, through provision of a simplified shedding mechanism which, except for the operation of a control element, is automatic in its operation both as to reversing and re-setting; which does not entail the exercise of any special skill on the part of the weaver; and which is operable by power incident to effecting the reversal. The reversing and re-setting is thus accomplished with a minimum loss of time and minimum curtailment in the output of the loom.

Other objects and attendant advantages will appear from the following detailed description of the attached drawings, wherein Fig. 1 is a fragmentary view in end elevation of a loom embodying a preferred form of the improved shedding mechanism of my invention.

Fig. 2 is a fragmentary view in elevation looking as indicated by the angled arrows II—II in Fig. 1.

Fig. 3 is a horizontal section taken as indicated by the angled arrows III—III in Fig. 1.

Fig. 4 is a fragmentary view in horizontal section taken as indicated by the angled arrows IV—IV in Fig. 2.

Fig. 5 is a fragmentary view showing the head motion in longitudinal section.

2

Fig. 6 is a fragmentary detail view in top plan looking as indicated by the angled arrows VI—VI in Fig. 1, with certain parts shown in section.

Fig. 7 is a fragmentary view in side elevation of the loom showing a means for bringing the crank shaft of the loom to a definite stop point in its rotation in preparation for reversal of the shedding mechanism; and

Fig. 8 is a fragmentary view in horizontal section taken as indicated by the angled arrows VIII—VIII in Fig. 7.

With more detailed reference, first more particularly to Figs. 1 and 5 of these illustrations, the usual jacks by which the shedding harnesses (not shown) are raised and lowered in the weaving are designated 1, said jacks being arranged side by side for independent rocking movement on a non-rotating shaft 2 extending transversely between the side frames 3 of the head motion of the loom. Functioning of the jacks 1 is selectively controlled by risers and sinkers 4, 4a, variously arranged on the cross rods 5 of a pattern chain 6 which is trained about sprocket wheels 7 on a transverse shaft 8 journalled in fixed bracket 9. The jacks 1 are actuated under control of pattern chain 6, as is customary, through means including a set of overlying vibrator levers 10 which are fulcrumed for independent movement on another fixed cross shaft 11, and which medially of their lengths and 15 at their bottoms, have cam lugs 10a for engagement by the risers and sinkers 4, 4a on the chain 6. Each vibrator lever 10 carries a mutilated spur pinion 12 with an eccentrically disposed crank pin 13 thereon connected by a link 15 to the upright arm of a corresponding jack 1, said pinion being restricted to a semirotation by virtue of having an arcuate slot 16 therein to cooperate with a lateral stop stud 17 on said lever. The head motion further includes the usual mutilated 20 cylinder gears 20, 21 which are affixed respectively to transverse shafts 22, 23 journalled in the side frames 3, shaft 22 being provided at one end with a hand wheel 24 whereby it may be manually rotated. Through bevel gear couples 25, 26, the shafts 22 and 23 are constantly rotated during the weaving, from a vertically arranged shaft 27. Secured to chain sprocket shaft 8 at the end thereof nearest the observer in Fig. 1, is a mutilated wheel 30 which is actuated through successive engagement of its round-bottomed peripheral notches, by a roller at the end of a short crank arm 31 on a constantly revolving subjacent shaft 32 rotatively supported in bracket 9. Normally, during the weaving, the several shafts thus far referred to turn in the directions of the arrows thereon in Fig. 1, all of them deriving their

motion from the crank shaft 33 of the loom in a manner and by means presently described. A reversible electric motor is shown at 34 in Fig. 7 as a power means for driving the loom.

It is to be noted, that, in accordance with my invention, vertical shaft 27 has affixed to its lower end, a bevel gear pinion 35 that meshes with opposingly arranged bevel gears 36 and 37 on a horizontal transmission shaft 38 journalled in stationary bearings 39 at a level somewhat below the crank shaft 33. As best seen in Fig. 3, the gears 36 and 37 are held against axial displacement on shaft 33 by collars 39, 40 set-screwed and keyed to said shaft. Likewise loosely mounted on shaft 38 are slide collars 41 and 42 with eccentrically-disposed studs 43, 44 which pass through fixed collars 39, 40, and which are adapted to engage respectively into correspondingly-disposed apertures 45, 46 in the bevel gears 36, 37. The collars 41, 42 are circumferentially grooved for engagement by the forked arms 47, 48 of a clutch yoke 49 which is shiftable endwise on a stationary parallel shaft 50 supported in bearings 51. Normally, collars 41 and 42 occupy the positions in which they are shown in Fig. 3, i. e. with pin 43 entered into gear 36, and with pin 44 retracted from gear 37. Under these conditions gear 36 will act as the driver for pinion 35, while gear 37 rotates idly about shaft 38. For reverse actuation of the shedding mechanism as later on explained, clutch yoke 49 is shifted leftward in Fig. 3 to couple gear 37 to shaft 38 with release, at the same time, of gear 36, whereupon on reversal of crank shaft 33, the vertical shaft 27 will be rotated in the same direction as before. The ball thrust bearings shown at 52 and 53 in Fig. 3 take the end thrust of shaft 38 when collars 41 and 42 are shifted as just described. As a means for effecting this shifting, I have provided a horizontally-arranged hand lever 55 which is fulcrumed at 56 on the frame 57 of the loom at a location convenient to the weaver. Lever 55 is connected, by means of a horizontal link 58, to one arm of a motion-translating bell crank lever 59 whereof the other arm is connected in turn, by a drop link 60, to the horizontal extremity 61 of a tri-arm 62, see Fig. 1. As shown, tri-arm 62 is fulcrumed on a fixed stud 63 on the loom frame, its upward extremity 65 being longitudinally slotted to engage a lateral stud projection 66 on the boss of sleeve portion of clutch yoke 49. Hand lever 55 is flexible so as to be selectively engageable with restraining notches 67, 68 in a keeper projection 69 on the loom frame.

The drive connections for the shaft 32 of the pattern chain progressing means include a spiral gear wheel 70 on said shaft, and an intermeshing spiral gear wheel 71 at one end of a horizontal shaft 72 rotatively supported in stationary bearings 73 and 74. A miter gear pinion 75 at the opposite end of shaft 72 meshes with a companion pinion 76 at the top of another vertical shaft 77 which likewise is journalled in fixed bearings 78 and 79 on the frame of the loom. A miter gear pinion 80 at the lower end of shaft 77 meshes, in turn, with a companion miter gear 81 which is free on shaft 50. Gear 81 is secured to a spur wheel 82 in mesh with a spur wheel 83 which, together with a somewhat larger spur wheel 85, is keyed to shaft 38. Spur wheel 85 meshes with a spur wheel 86 loose on a counter shaft 87 (Figs. 2 and 4) which is journalled in stationary bearings 88 and 89, and which is driven, through a pair of intermeshing spur gears 90

and 91, from the crank shaft 33 of the loom. Spur wheel 86 has an eccentrically-disposed aperture 92 (Fig. 4) adapted to be entered by a crank pin 93 on a rotatively-free but shiftable collar 95 on shaft 87, said pin passing through a collar 96 which is set screwed and keyed to said shaft alongside said spur wheel. Clutch collar 95 is engaged by a shifting fork 97 on a shaft 98 rotatively supported in a pair of spaced stationary bearings 99, 100. Secured to shaft 98, between the bearings 99 and 100, is a gear sector 101 that meshes with a spur pinion 102 on a shaft 103 borne in lateral bracket projects 105 and 106 of said bearings. Shaft 103 is rockable by means of a hand lever 107 between limits imposed by stops 108, 109 on the bracket projection 105, to shift the clutch collar 95, said hand lever being weighted as at 110 for maintenance against accidental displacement from either position to which it may be thrown.

From Fig. 6, it will be noted that wheel 30 of the pattern chain actuating mechanism is loose on shaft 8 and has a miter gear pinion 111 affixed to its hub sleeve. An arm 112 fulcrumed for independent movement about shaft 8, carries a freely-rotative miter gear pinion 113 which meshes not only with the pinion 111, but also with a pinion 115 pinned to said shaft. By means of a drop link 116 (Fig. 1) the arm 112 is coupled with an arm 117 fast on a shaft 118 which latter is rockable in stationary bearings 119. A second arm 120 on shaft 118 is coupled by means of a short horizontal link 121 to the pendant extremity 122 of the tri-arm 62 previously referred to. By the arrangement just described, the pattern chain actuating shaft 8 is turned counterclockwise in Fig. 1 through a partial rotation, as will be presently seen, when hand lever 55 (Fig. 3) is thrown to reversely operate the shedding mechanism. The weight indicated at 125 tends to restore the shaft 118 and the parts connected thereto to the normal position in which they are shown in Fig. 1.

During weaving, crank shaft 33 rotates clockwise as indicated at the arrow in Fig. 3, and in order to determine a definite stop position for it in preparation for reversal of the shedding mechanism, I have provided the means disclosed in Figs. 7 and 8. As shown, this means includes a detent 130 which is pivoted at 131 on the loom framework, and which is adapted to cooperate with the stop projection or tooth 132 of a collar 133 affixed, by means of a plurality of circumferentially-arranged screws 134, to a spur gear 135 on the crank shaft 33. Detent 130 normally occupies the lowered position in which it is illustrated in full lines in Fig. 7, but can be raised to the broken line position through engagement of a radical lug 136 on its hub by the downwardly and rearwardly directed end 137 of a rod 138 which is sustained for horizontal sliding movement in fixed guides 139, 140 on the loom framework, and which is connected to one arm of a bell crank lever 141 fulcrumed at 142. The other arm of bell crank lever 141 is coupled, by a drop link 143, with an arm 145 fulcrumed at 146 on the loom framework. A tension spring 147, influential upon arm 145, is relied upon to normally maintain the parts 138, 141 and 143 positioned to allow the detent to take its lowered active position, with a control treadle extension 148 of said arm stopped against a lateral stud projection 149 on the framework of the loom. By depressing the pedal 148, the detent 130 will be raised from the active position in which it is

shown in Fig. 7 to clear the stop projection 132 of collar 133.

The let-off motion, the take-up motion and the weft detector stop motion of the loom may be of any of the well-known and approved prior art constructions and have therefore not been illustrated; and it is to be assumed, that the loom is provided with manual switch means for controlling the motor 34 in forward and reverse driving the loom as well as jogging the loom either forwardly or reversely.

Operation

Let it be assumed that the loom has been stopped upon detection of shuttle exhaustion or breaking of the weft thread. Upon occurrence of such contingency, the weaver starts drive motor 34 in reverse under jog control, whereby crank shaft 33 is "inched" about counterclockwise in Fig. 7, until stopped by engagement of the tooth 132 on collar 133 with detent 130 as in Fig. 7. As a result, the various moving parts of the shedding mechanism will be positioned in readiness for clutch shifting by means of the hand lever 55 (Fig. 3) which is then thrown to "Reverse" and locked into recess 67 of the keeper projection 69. As lever 55 is so thrown, yoke 49 will be shifted to the left in Fig. 3, whereby bevel gear 36 will be released from shaft 38 and bevel gear 37 clutched to said shaft. At the same time, through the linkage 58, 59, 60, 61, 122, 121, 120, 117 and 116, arm 112 will be moved downward to the broken line position in Fig. 1. By incidental action of the differential gear set 111, 113, 115 (Fig. 6) a partial turn will be imparted counterclockwise to pattern chain sprocket shaft 8 alone, i. e., independently of notched wheel 30. As a consequence, pattern chain 6 will be backed off by one step. With this preparation, foot treadle 148 is depressed to lift detent 130 to its retracted position and the loom jogged to operate by power in reverse. Shafts 71, 72, 32 will be rotated in reverse and through arm 31 and notched wheel 30, pattern chain 6 will be backed off one step for each reverse rotation of crank shaft 33. During this re-setting of the head motion, the direction of rotation of cylinder gear shafts 22 and 23 will remain the same as during normal operation of the loom, due to substitution of bevel gear 37 for bevel gear 36 to drive vertical shaft 27 brought about by the shifting of clutch yoke 49. The number of times pattern chain 6 is stepped back will of course depend upon the extent that the loom has over-run after weft failure. In any event, the corrective procedure will be terminated with crank shaft 33 positioned as in Fig. 7, i. e., with the collar 132 stopped by detent 130, when clutch pin 43 on collar 39 (Fig. 3) will again be in line with hole 45 in bevel gear 36. With this accomplished, the broken weft ends are tied together or a new weft supply provided in the shuttle as may be required, whereupon hand lever 55 is returned to the "Forward" position for restoration of all of the parts of the drive mechanism to the normal positions in which they are illustrated in full lines in the drawings, with incidental advance of the pattern by a single step. The loom is then finally re-started for operation as usual to continue with the weaving.

When pattern chain 6 is to be changed or another is to be substituted for it for the production of a different weave in the loom, the shedding drive mechanism is disconnected from crank shaft 33 by throwing weight lever 110 from the full lines position of Fig. 3 to the position of Fig.

4, whereby clutch 95 is shifted to release spur wheel 86 on shaft 87. The head motion can then be operated alone by means of hand wheel 24, without the necessity for exertion of undue manual effort on the part of the loom attendant.

From the above description it will be seen that I have provided a novel head motion drive mechanism in which the usual harness actuating means is driven from a rotating shaft separate from the shaft which actuates the pattern control mechanism. On reversal of the drive shaft of the main power source for driving the loom, the direction of rotation of the harness actuating shaft may be maintained constant throughout operation by means which I have devised, while the shaft for operating the pattern control means undergoes a reversal in direction. It will furthermore be seen that I have provided interconnecting means by which the pattern control means is automatically backed off or advanced when the means for maintaining constant direction of rotation of the harness actuating shaft is operated.

While a preferred embodiment of the present invention has been shown in the drawings and described in the specification, it is intended that equivalent means for effecting the novel operation and control of the present invention shall be included within its scope as defined in the following claims.

Having thus described my invention, I claim:

1. In a loom, a head motion including pattern control means and harness actuating means, a source of power for driving said loom, reversing means operatively connected with said source of power, means including a rotatable shaft operatively connecting said power source with said pattern control means and means including a separate rotatable shaft operatively connecting said power source with said harness actuating means, rotatable control means for maintaining constant the direction of rotation of said harness actuating shaft on reversal of said power source and attendant reversal of the direction of rotation of said pattern control operating shaft, and means operatively connected with said rotational control means and said pattern control means whereby said pattern control means is backed on operation of said rotational control means in one direction and advanced on operation of said rotational control means in the other direction.

2. The invention according to claim 1, further characterized by means for operating said pattern control means, and means whereby said pattern control is backed by a single step on operation of said rotational control means in one direction and advanced by a single step on operation of said rotational control means in the other direction.

3. The invention according to claim 1 further characterized by the fact that said pattern control backing and advancing means includes a differential gear set automatically moveable on operation of said rotational control means.

4. In shedding mechanism for a loom having a main drive shaft, said mechanism comprising a plurality of harness lifting jacks; a pair of cylinder gears and interposed selective instrumentalities through which the jacks are actuated from the cylinder gears; pattern mechanism including a sprocket chain adapted to be moved through a definite increment thereby variably selecting said instrumentalities for successive shed changes during weaving; a transmission shaft deriving its rotation from the drive shaft; drive connections through which the chain is operated as aforesaid

from the transmission shaft, a pair of opposingly arranged bevel gears free on the transmission shaft; a take-off shaft through which rotary motion is imparted to the cylinder gears; a bevel pinion fixed upon the take-off shaft in constant mesh with the opposed bevel gears on the transmission shaft; and a clutch whereby the opposed bevel gears can be selectively clutched to the transmission shaft so that the direction of rotation of the cylinder gears will not be changed when the drive shaft and the pattern chain are reversed to re-set the loom in making corrections for weft failure.

5. The invention, according to claim 4, wherein the drive shaft is powered by a reversible electric motor.

6. The invention, according to claim 4, wherein the loom is powered by a reversible electric motor; and further including manual clutch means for releasing and engaging the gear connections between the drive shaft and the transmission shaft, as and for the purpose set forth.

7. The invention accordance to claim 4, further including means for determining a definite stop position in the rotation of the drive shaft so that the bevel gears on the transmission shaft will be in proper register for release of one and coupling of the other as the clutch is operated.

8. The invention, according to claim 4, further including means for determining a definite stop position in the rotation of the drive shaft so that the bevel gears on the transmission shaft will be in proper register for release of one and coupling of the other as the clutch is thrown, the last mentioned means including a fixed collar on the drive shaft having a radially projecting stop tooth, a detent to cooperate with the said tooth, and treadle means for controlling the detent.

9. The invention, according to claim 4, further including means automatically operative to back off the pattern chain sprocket by one step as the clutch is thrown preparatory to reversing the shedding mechanism to re-set the latter upon weft failure.

10. In shedding mechanism for a loom capable of being reversed for re-setting in the event of weft failure; said mechanism comprising a plurality of harness lifting jacks; actuating means including selector's for said jacks; a pattern chain adapted to be moved through a definite increment thereby variably selecting said selectors for successive actuations of the harnesses; a shaft with a sprocket affixed thereto about which the pattern chain is trained; drive means for rotating the sprocket shaft; means operative at the initiation of loom reversal to reversely rotate the sprocket shaft and thereby back off the chain to the extent of one increment of movement, and, at the completion of the reversal to advance said chain by one increment.

11. In shedding mechanism for a loom capable of being reversed for re-setting in the event of weft failure, said mechanism comprising a plurality of harness lifting jacks; actuating means including selector's for said jacks; a pattern chain adapted to be moved through a definite increment in variably selecting said selectors for successive actuations of the harnesses; a shaft with a sprocket affixed thereto about which the pattern chain is trained; drive means for rotating the sprocket shaft; means operative at the initiation of loom reversal to reversely rotate the sprocket shaft and thereby back off the chain to the extent of one increment, and, at the completion of the reversal, to advance said chain by one increment said means including a loose wheel on the

sprocket shaft and differential gear means with a bevel pinion carried by an arm also free on the sprocket shaft in mesh with oppositely-arranged bevel gears respectively affixed to said shaft and said wheel; and means whereby said arm is moved at the initiation of loom reversal to effect, through the differential, reverse rotation of the sprocket shaft independently of the wheel thereon, for back stepping of the pattern chain to the extent of one increment, and whereby said arm is oppositely moved, at the completion of the reversal, to advance the chain by one increment.

12. In shedding mechanism for a loom with a main shaft capable of being reversed for re-setting in loom in the event of weft failure, said mechanism comprising a plurality of harness lifting jacks; a pair of cylinder gears and interposed selective instrumentalities through which the jacks are operated from the cylinder gears; a drive shaft for imparting rotary movement to the gear cylinders; a pattern chain adapted to be moved through a definite increment each time in variably selecting said instrumentalities for successive actuations of the harnesses; a shaft with a sprocket affixed thereto about which the pattern chain is trained; a wheel loosely mounted on the sprocket shaft; differential gear means with a bevel pinion carried by an arm also loosely mounted on the sprocket shaft, in mesh with a pair of opposingly-arranged bevel gears respectively affixed to said shaft and to the wheel; a transmission shaft geared to the loom shaft; a drive shaft geared to the transmission shaft for rotating the wheel on the sprocket shaft; change gears interposed between the transmission shaft and the drive shaft for the cylinder gears; clutch means adapted to be operated in preparation for loom reversal to arrange the change gears so that the cylinder gears are rotated in the same direction during reversal as during normal weaving; and means automatically actuated by operation of the clutch means to move the arm aforesaid, whereby, through the differential gear means, the sprocket shaft is reversely rotated to back off the chain to the extent of one increment.

13. In shedding mechanism for a loom having a reversible drive means, said shedding mechanism including harness-actuating means; pattern control means for the harness actuating means, interposed means through which the pattern means is operated from the loom drive means and reversed upon reversal of the loom in making correction for weft failures; and separate interposed means through which the harness actuating means is operated from the loom driving means in one direction both during normal weaving and during loom reversal.

14. Shedding mechanism, according to claim 13 in which the pattern means includes a chain adapted to be advanced by a definite increment for each harness actuation; and further comprising means automatically operative at the initiation of loom reversal, to step back the chain by one increment, and upon completion of the reversal to advance the chain by one increment before weaving is resumed.

15. In shedding mechanism for a loom having a reversible drive means, said shedding mechanism including harness-actuating means; pattern control means for the harness actuating means; a shaft with interposed gear connections through which the pattern means is operated from the loom drive means in one direction during normal weaving and in the opposite direction during loom reversal for correction of weft failure; a

separate shaft with interposed change gear connections through which the harness-actuating means is operated from the loom driving means in one direction both during normal weaving and during loom reversal.

16. Sheding mechanism, according to claim 15, in which the pattern means includes a chain adapted to be advanced by a definite increment for each harness actuation; and further comprising means automatically operative at the initiation of loom reversal, to step back the chain by one increment, and upon completion of the reversal to advance the chain by one increment before weaving is resumed.

17. In shedding mechanism for a loom having a drive shaft and reversible motor means for the drive shaft, said mechanism comprising a plurality of harness lifting jacks; a pair of cylinder gears and interposed selective instrumentalities through which the jacks are operated from the cylinder gears; a sprocket chain with means thereon for variously selecting said instrumentalities for operation during the weaving, a transmission shaft driven from the crank shaft of the loom, separate drive connections through which

the cylinder gears and the sprocket chain independently derive motion from the transmission shaft, and means whereby the drive connection to the cylinder gears can be set so that said gears will not be reversed in direction of rotation when the shedding mechanism and the loom are reversed in making corrections for weft failure.
